(57) **CLAIM**

The ornamental design for an antler ornament, as shown and described.

DESCRIPTION

FIG. 1 is a front perspective view of the antler ornament in accordance with this invention;

FIG. 2 is a front view of the design shown in FIG. 1;

FIG. 3 is a top view of the design shown in FIGS. 1 and 2;

FIG. 4 is a bottom view of the design shown in FIGS. 1-3;

FIG. 5 is a left side view of the design shown in FIGS. 1-4, with the right side view being a mirror image of FIG. 5; and, FIG. 6 is a rear perspective view of the design shown in FIGS. 1-5.

The broken line showing of an antler ornament is included for the purpose of illustrating environmental structure and forms no part of the claimed design.
